UNITED STATES PATENT OFFICE.

LOUIS D. SUMMERS, OF SPRINGFIELD, ILLINOIS, ASSIGNOR TO FIRM OF FRANZ AND SUMMERS, CONSISTING OF LOUIS D. SUMMERS, FRED FRANZ, JR., AND WILLIAM J. FRANZ, OF SPRINGFIELD, ILLINOIS.

HEAT ECONOMIZER FOR FURNACES.

Application filed January 14, 1925. Serial No. 2,317.

To all whom it may concern:

Be it known that I, LOUIS D. SUMMERS, a citizen of the United States, residing at 701 Fayette Ave., Springfield, in the county of 5 Sangamon and State of Illinois, have invented a new and useful Heat Economizer for Furnaces, of which the following is a specification.

My invention relates to devices that are 10 adapted to secure a maximum of benefit from the heat normally passing out of a furnace flue as wasted heat; an object being in this device not only to provide more heating surface but also to provide a device 15 that will temporarily retain the products of combustion from the furnace, within a chamber for heating a series of fresh air tubes where the fresh air is adapted to become heated on its circuit through the rooms 20 to which the heat is distributed.

A particular object of my invention is to provide a heat economizer to be used with oil, coke or gas burning furnaces and the like, that will be adapted to take advantage 25 of the control of the movement of the commonly wasted heat from the furnace in a manner that will most efficiently secure a maximum of benefit therefrom while the same is at its highest temperature. In the 30 meantime I provide in this same device a means for prolonging the time during which the hot gases will continue to heat the fresh air flues.

My invention embodies a construction of 35 heat economizer that is adapted to be made of metallic parts such as galvanized sheet iron or the like together with such other details of construction that will combine the merits of strength and scientific relation of 40 parts for this purpose.

The intended novel features of construction of my device will be hereinafter more 45 fully described in the annexed specification, recited in the claim and illustrated in the accompanying drawings, in which like reference numerals indicate the same structural parts in the figures.

Referring to the drawings, Fig. 1 is a perspective of the heat economizer of my invention 50 partially cut away, showing the interior construction and in general showing the relation of the economizer in its several details to a furnace with which it may be operatively connected.

Fig. 2 is a vertical section of the heat 55 economizer of my invention showing therein the related details of construction and operation thereof.

The preferred embodiment of my invention and the methods of securing the 60 desired results therein will now be pointed out, as references are made to the several numerals in the respective figures illustrating the device of my invention.

Among other successful arrangements by 65 which intended results may be secured by gravity feed and the like with a heat economizer of my invention is an arrangement illustrated in Fig. 1 whereby a furnace —3— in being used as an oil, coke or gas burning 70 furnace may be provided with a blower pipe —2— and a motor driven blower —1— which is adapted to force a draft for the burning oil fuel. In this connection attention is called to the fact that normally a 75 furnace is provided with a cold air intake —15— and a series of heat distributing units —5— and a flue pipe —6— which has been normally connected to a house flue heretofore, but in the heat economizer of my invention I provide an upright drum —9— having a heating hood —11— which hood is provided with a series of heat distributing 80 units —12— and a secure cover —18—. Drum —9— is adapted to be mounted upon and 85 secured to a cold air intake compartment —4— the interior of which compartment is shown at —7—. Heating hood —11— provides a heat accumulating chamber for 90 heated fresh air, and this hood compartment communicates with fresh air intake compartment —7— below, through a series of up-right, parallel, spaced, heat conducting, fresh air communicating flues —10—. These flues are shown with the upper parts of most 95 of the same cut off in order to more clearly illustrate their spaced relation.

It will be seen that the products of combustion that normally pass out of flue —6— and become wasted are in this case directed 100 to a centrally disposed chamber for economizing the same.

This economizing chamber is formed by a base plate —17— secured to an opening of like size in pipe —4—. This base plate is 105 provided with a plurality of spaced apertures over which a like number of fresh air flues —10— are seated and welded; and in

this connection it will be noted in Fig. 1 that said fresh air flues are arranged in convenient up-right parallel spaced relation.

The top ends of this group of fresh air flues are secured to a second metallic plate —16— similar to plate —17— and having a similar number of apertures therein and each in vertical alignment with a corresponding aperture in the lower plate. It will be noted that the upper ends of the above mentioned fresh air flues are each secured to plate —16— and so positioned as to communicate with the corresponding apertures within.

15 A sheet of galvanized iron forming the drum —9— encompasses plates —16— and —17— in the preferred manner illustrated in Fig. 1 and is secured to these plates so as to encompass the periphery thereof. A heating hood —11— is mounted upon and coinciding with the periphery of drum —9— which normally communicates with pipe —4— through fresh air flue pipes —10—.

With this arrangement it will be seen that 25 the enclosing drum —9— forms a gas chamber —8— through which flues —10— extend.

In setting up the economizer, drum —9— with its contents, including the upper and 30 lower plates and the group of fresh air communicating tubes, is seated into position upon pipe —4— after which heating hood —11— is fitted into place on top of drum —9— where it is secured by fasteners —19— and fits drum —9— along line —20—.

After the economizer of my invention has been assembled in a correct manner the intended method of operating the same is as follows: The circulating fresh air comes into 40 pipe —4— through intake pipe —15— to the hot air hood of the furnace while another part of it passes up through the group of fresh air communicating tubes —10— and becomes heated while thus passing, after 45 which it passes on to heating hood —11— from which it is normally distributed through pipes —12— to the desired rooms for heating the same.

The products of combustion without this 50 economizer would normally pass out to the house chimney flue —14— through pipe —6—, but I accomplish with the device of my invention a decided economy in heating, by saving and utilizing this heat that normally has been going up the chimney. I 55 accomplish this economy of heat by running the products of combustion through pipe —6— from the furnace into the upper side wall of chamber —8— where it will be seen that the said products of combustion will be thrown into contact with the external surface of the fresh air flues —10— as they extend up through chamber —8—. Here it will be seen that when the heated gases heat 60 the group of up-right fresh air flues it causes

the fresh air which passes there-through to become heated by conduction.

In this connection it will be particularly noted that the hot gases entering chamber —8— enter at the maximum temperature 70 coming from the furnace through flue —6— and naturally will produce the greatest heat about the upper ends of the flues —10—; but as it gradually tends to get cooler it will normally settle slowly to a lower level. 75 When it has reached its coolest relative temperature while in chamber —8— it will be at the bottom thereof and will then pass out to the house chimney through pipe —13—.

It will therefore be seen that the products of combustion do not pass out of chamber 80 —8— until they have settled to a low level by heat gravitation through gradually lowering temperatures before passing out to the house chimney, through pipe —13— which connects with the lower side wall of drum —9— for the normal discharge of said products of combustion.

To those skilled in the art it will be evident that a conspicuous merit in the economizer of my invention lies in the detail of construction which permits the heated gases from flue —6— to remain in heat chamber —8— in contact with flue pipes —10— for an extended length of time before surrendering their greatest temperature and more especially do these gases heat the fresh air flues at their upper end which is nearest the heat accumulating hood —11— from which the heated fresh air is promptly distributed through distributing units —12—. It will be observed that flues —10— by being in an up-right position are adapted to continue to be heated by the products of combustion even while such gases are going through the process of surrendering temperature and settling to a lower level through heat gravitation.

It will also be evident to those skilled in the art that this economizer may be adaptable to certain minor changes without departing from the spirit and scope of this invention or sacrificing any of the intended merits thereon; it being evident, for instance 110 that the heating drum —9— which encompasses the heating chamber could be cylindrical or rectangular rather than hexagonal as shown.

Having thus described the nature of my invention what I claim as new and useful and desire to secure by Letters Patent is:

A heat economizer of the character described spaced from and operatively connected with an oil or coal burning furnace; 125 said economizer comprising an upright drum including an upper detachable fresh air accumulating hood for heated fresh air, a chamber for the accommodation of the heated products of combustion from the furnace 130

and a plurality of upright parallel fresh air communicating tubes extending through said chamber; a fresh air intake pipe adapted to simultaneously supply fresh air for the furnace to heat and fresh air for the economizer to heat; said hood provided with a plurality of heat distributing units and said chamber of the economizer connected with the flue of the furnace at the upper portion of the

chamber and provided with an outlet flue 10 communicating with the lower end of the chamber so as to utilize to the maximum extent the heated gases emanating from the furnace.

In witness whereof I hereunto set my 15 hand and seal this 10th day of January, A. D. 1924.

LOUIS D. SUMMERS. [L. S.]
